UNITED STATES PATENT OFFICE.

JAMES CHILDS, OF BARROW-IN-FURNESS, ENGLAND, ASSIGNOR TO VICKERS LIMITED, OF WESTMINSTER, ENGLAND, A BRITISH COMPANY.

ROTARY DRILLING MACHINE OF WELL-BORING APPARATUS.

Application filed July 15, 1924, Serial No. 726,110, and in Great Britain September 1, 1923.

This invention relates to the rotary drilling machines of well boring apparatus. Such machines as heretofore constructed have usually had keyed to the driving pinion shaft a locking collar with which pawls pivoted on the bedplate are adapted to engage so as to prevent the turntable driven by the said shaft from rotating while tool joints or couplings are being tightened up or slackened off by hand. It sometimes happens that an attempt is made to start the machine with the said pawls left in engagement with the locking collar, with the result that the driving chain or other parts of the driving mechanism are liable to become broken with possible injury to men on the derrick floor; the chief object of the present invention is to obviate this disadvantage.

According to the invention the aforesaid locking collar instead of being keyed to the driving pinion shaft as heretofore is connected thereto through a device which, in the event of the machine being started with the aforesaid pawls in engagement with the locking collar, will slip and thereby permit the turntable to be revolved without damage to any part of the driving mechanism. The said device is preferably constituted by a cone or other friction clutch one element of which forms part of the locking collar loosely mounted on the pinion shaft, and the other element is keyed to the pinion shaft; in the case of a chain driven machine the latter clutch element may be made integral with or separate from the driven sprocket wheel, and in the case of a shaft driven machine this clutch element may also be separate from the sprocket wheel which in this form of machine is external to the parts carried by the bedplate.

In order that the said invention may be clearly understood and readily carried into effect the same will now be described more fully with reference to the accompanying drawings, in which:—

Figures 1, 2 and 3 are respectively a plan, a section on the line 2, 2 of Figure 1 and a section on the line 3, 3 of Figure 1 shewing 50 a rotary drilling machine provided with one constructional form of the invention.

Figure 4 is a view similar to Figure 1 shewing in less detail a rotary drilling machine provided with a slightly modified constructional form of the invention,

Figure 5 is a local section taken on the line 5, 5 of Figure 4, and

Figures 6 and 7 are views similar to Figures 4 and 5 (Figure 7 being a section on the line 7, 7 of Figure 6) shewing the invention employed in conjunction with a somewhat different form of rotary drilling machine.

A is the turntable having bevel teeth *a* with which a bevel pinion *b* on a driving shaft B engages. C is the locking collar with which pawls *c*, *c* pivoted on the bedplate D are adapted to engage. The locking collar has heretofore been keyed to the driving shaft B but in the present invention it is loosely mounted on the said shaft and is formed with a part C' constituting one element of a cone clutch the other element of which is constituted by a member B' keyed to the driving shaft B. The unit constituted by the locking collar C and the clutch element C' is adjusted relatively to the clutch element B' by means of a nut *c'* on the shaft B between which nut and the collar C a spring washer *c''* is interposed. The nut *c'* is locked in position by a locking nut *c''* on the shaft B. In the construction shewn by Figures 1 to 3 the clutch element B' is made as a sprocket wheel for driving the shaft B by means of a chain, whilst in the construction shewn by Figures 4 and 5 the clutch element B' (which is here the male element) is made separate from the sprocket wheel B² and the elements B' and C' together with the parts associated therewith are arranged at the end of the driving shaft B. In other respects these two constructions are substantially the same. In Figures 6 and 7 the elements B' and C' and the parts associated therewith are arranged as in Figures 1 to 3 but the sprocket wheel B² is connected to a shaft b² which is external to the parts carried by the bedplate D and is connected to the driving shaft B by the bevel gearing shewn in Figure 6. In any of the said constructions the cone clutch constituted by the elements B', C' may be replaced by any other suitable type of friction clutch.

It will be understood that in all the constructions shewn the pawls *c*, *c* are normally kept out of engagement with the locking collar C so that when the turntable A is driven from the shaft B the locking collar C is rotated through the friction clutch B', C'. When tool joints or couplings are to be

tightened up or slackened off by hand, the prime mover is stopped and the pawls *c, c* are moved into engagement with the locking collar *C*. If, whilst the said pawls are 5 in engagement, an attempt is made to start the machine, the clutch element *B'* connected to the shaft *B* will slip with respect to the clutch element *C'* held by the pawls *c, c* and the turntable *A* will be rotated, thereby 10 avoiding the liability of the driving chain or other parts of the driving mechanism becoming broken.

What I claim and desire to secure by Letters Patent of the United States is:—

15 1. In a rotary well drilling machine having a turntable and a shaft for driving said turntable the combination with said shaft of a locking collar loosely mounted thereon, a pawl adapted to engage with said collar 20 to prevent rotation thereof, and a device secured to said shaft for impositively connecting said collar to said shaft to yieldably lock said shaft against rotation when said pawl is in engagement with said collar, 25 whereby if said machine is started while said shaft is yieldably locked, said device will slip and permit said shaft to rotate said turntable.

30 2. In a rotary well drilling machine having a turntable and a shaft for driving said turntable the combination with said shaft of a locking collar loosely mounted thereon, a pawl adapted to engage with said collar to prevent rotation thereof, and a friction 35 clutch for impositively connecting said collar to said shaft to yieldably lock said shaft against rotation when said pawl is in engagement with said collar, whereby if said machine is started while said shaft is yield-

ably locked, said clutch will slip and permit 40 said shaft to rotate said turntable.

3. In a rotary well drilling machine having a turntable and a shaft for driving said turntable the combination with said shaft of a locking collar loosely mounted thereon, a 45 pawl adapted to engage with said collar to permit rotation thereof, and a friction clutch one element of which forms a part of said collar and the other of which is secured to said shaft for impositively connecting 50 said collar to said shaft to yieldably lock said shaft against rotation when said pawl is in engagement with said collar, whereby if said machine is started while said shaft is yieldably locked, said clutch will slip 55 and permit said shaft to rotate said turntable.

4. In a rotary well drilling machine having a bed-plate carrying a turntable and a shaft for driving said turntable the combination with said shaft of a locking collar loosely mounted thereon, a pawl pivoted to said bed-plate and adapted to engage with said collar to prevent rotation thereof, a friction clutch one element of which forms 60 a part of said collar and the other of which is secured to said drive shaft to yieldably lock said drive shaft against rotation when said pawl is in engagement with said collar, a power shaft arranged external to said 65 bed-plate, and means for transmitting motion from said external shaft to said drive shaft, whereby if said machine is started while said drive shaft is yieldably locked, 70 said clutch will slip and permit said drive shaft to rotate said turntable.

JAMES CHILDS.
